UNITED STATES PATENT OFFICE

2,652,704

KNITTING MACHINE

Robert H. Roughsedge, Ramsey, N. J., and Hans G. Lustig, New York, N. Y., assignors to Celanese Corporation of America, a corporation of Delaware

Application July 22, 1948, Serial No. 40,116

19 Claims. (Cl. 66—149)

1

This invention relates to knitting machines, and relates more particularly to a novel fabric take-up mechanism of a warp knitting machine.

In the production of knitted fabrics, it is customary to pass the fabric, after it leaves the knitting station, around a feed roll to a cloth-roll or take-up roll upon which the fabric is wound, and which holds from fifty to one hundred or more yards of fabric when full. The feed roll is driven intermittently, in timed relation to the knitting cycle, to maintain a constant tension on the fabric and to draw the fabric from the knitting station at the proper instant during the knitting of each course. The cloth-roll rests on the feed roll and is driven through frictional contact therewith, but as knitting proceeds additional torque must be applied to the cloth-roll to obtain a tight, uniform winding of the fabric. The need for this additional torque arises from the fact that as the amount of fabric on the cloth-roll increases the force necessary to drive said cloth-roll must be transmitted from the feed roll through an ever larger number of layers of warp-knitted fabric. Thus, although the frictional contact between the feed roll and the outer layer of fabric on the cloth-roll is sufficient at all times to avoid slippage therebetween, the frictional forces between the several layers of fabric wound on said cloth-roll have been found to be inadequate to provide for driving the cloth-roll at a sufficiently high speed to obtain a tightly wound roll. Instead, because of the slippage which takes place between the several layers of fabric on the cloth-roll, it has been found that there is a tendency to produce an extremely loose winding on the said cloth-roll which is commercially unsatisfactory. It has been found that the additional torque required to obtain a tight, uniform winding of the fabric increases from a minimum when the cloth-roll is empty, to a maximum when the cloth-roll is partly full, and remains constant at this maximum value until the cloth-roll is completely filled and ready to be removed from the machine.

It is, accordingly, an important object of this invention to provide a relatively simple mechanism which will automatically apply the required torque to the cloth-roll of a knitting machine.

A further object of this invention is to provide a relatively simple mechanism, which will automatically increase the torque applied to the cloth-roll of a knitting machine from a minimum when the cloth-roll is empty, to a maximum when the cloth-roll is partly full, and will maintain the torque at this maximum value until the cloth-roll is completely filled.

2

Other objects of this invention, together with certain details of construction and combinations of parts, will be apparent from the following detailed description and claims.

5 While our invention will be described in connection with a two-bar warp knitting machine, it is to be understood that it is equally applicable to any warp knitting machine.

In the drawings, wherein a preferred embodiment of our invention is shown,

Figure 1 is a fragmentary side-elevational view, partly in section, of a warp knitting machine embodying our invention.

10 Figure 2 is a fragmentary front-elevational view of the warp knitting machine shown in Figure 1.

Figure 3 is a detail view in cross-section of the driving mechanism for the feed roll, taken on line 3—3 in Figure 4.

15 Figure 4 is a detail view in side-elevation of the driving mechanism for the feed roll.

Figure 5 is a front-elevational view, partly in section and on an enlarged scale of the driven end of the feed roll,

20 Figure 6 is a side-elevational view of the driving mechanism for the cloth-roll,

Figure 7 is a cross-sectional view of the driving mechanism for the cloth-roll taken on line 7—7 in Figure 6,

25 Figure 8 is a cross-sectional view of the driving mechanism for the cloth-roll,

Figure 9 is a detail view of the barrel cam which forms a part of the driving mechanism for the cloth-roll,

30 Figure 10 is a detail view of the ring cam which forms a part of the driving mechanism for the cloth-roll, and

Figure 11 is a development of the camming surfaces on the barrel and ring cams shown in Figures 9 and 10.

35 Referring now to the drawings for a detailed description of this invention, the reference numerals 21 and 22 designate warp threads, which are led from any suitable source of supply such as warp beams (not shown), to a knitting station

40 indicated generally by reference numeral 23, where they are knitted to form a fabric 24 by means of knitting members 25. From the knitting station 23, the fabric passes over a deflector bar 27, under a feed roll 28 and is then wound on a cloth-roll 29.

45 The feed roll 28 may be a porcupine roll or a roll surfaced with a friction material such as emery to insure a positive grip on the fabric. In order to obtain a quality fabric from a high-speed warp knitting machine, it is 50 necessary as has been pointed out above, that the

feed roll 28 be driven in timed relation to the operation of the knitting members 26. To insure the proper sequence of operations, the feed roll 28 is positively driven by a driving mechanism, indicated generally by reference numeral 31, from the cam shaft 32 which drives the knitting members 26 in a manner well known in the art.

The cam shaft 32, which is driven by any suitable means (not shown), is journaled in frame members 33 and 34 and has an eccentric plate 36 fixed to its left end by means of a key 37 held in place by a set screw 38. The eccentric plate 36 is provided with ears 39 between which is mounted a second eccentric plate 41 having a plurality of slots 42 in each end. The two eccentric plates are adjustably fastened to each other by bolts 43 extending through the slots 42 and by screws 44 passing through the ears 39 to engage the ends of the plate 41. An eccentrically mounted stub shaft 46 extends through the plate 41 and is held in position by a flange 47 at the base thereof. Any desired degree of eccentric motion may be imparted to the stub shaft 46 by shifting the position of the eccentric plates relative to each other, such movement also shifting the position of the stub shaft 46 relative to the cam shaft 32.

Connecting rods 48 and 49 pivotally fastened to each other by means of a bolt 50 are mounted between the stub shaft 46 and a ratchet shaft 51 to transmit motion from the stub shaft to a ratchet wheel 52. Thus, connecting rod 48 is journaled on the stub shaft 46 and connecting rod 49 is journaled on the shaft 51. The latter connecting rod is provided with a pivotally mounted pawl 53, which together with a lock pawl arrangement indicated generally by reference numeral 54 drives the ratchet wheel 52. One end 56 of the pawl 53 is urged into engagement with teeth 57 on the ratchet wheel 52 by means of spring 58 which is fastened between the other end of the pawl 53 and the connecting rod 48.

The lock pawl arrangement 54 is carried by a shaft 59, fastened in frame member 61 by a set screw 62, and said shaft has at its free end an enlarged head 63. Encircling the shaft 59 is a helical spring 64 having one end fastened in a slot 66 in the head 63 and its other end secured to a pawl 67, the spring being adapted to urge the pawl into engagement with the teeth 57. The spring pressure on the pawl 67 may be varied by loosening the set screw 62 and rotating the head 63 to obtain the desired tension in the spring 64.

The ratchet wheel 52 is held on the ratchet shaft 51 by means of a key 68 whereby the motion imparted to the ratchet wheel by the pawl 53 will be transmitted to a bevel gear 69 mounted on the other end of the ratchet shaft 51 by means of a key 70. The bevel gear 69 meshes with and drives a second bevel gear 71, which in turn drives a worm 72 through a shaft 73 journaled in a bearing bracket 74. The worm 72 meshes with and rotates a worm wheel 75 which is attached to a shaft 76 by means of a key 77 held in position by a set screw 78. One end of the shaft 76 is fastened to and supports the feed roll 28, the rotation of shaft 76 rotating the feed roll in timed relation to the knitting cycle. The other end of the shaft 76 is journaled in a bearing 79 supported in the frame member 33, the shaft being held in the bearing 79 by means of a collar 80 fastened to the outer end of the shaft by a set screw 81. The other end of the feed roll is fastened to and supported by a shaft 82 jour-

nalled in a bearing 83 carried in the other frame member 34.

The cloth-roll 29 is driven from the feed roll 28 by means of a take-up drive indicated generally by reference numeral 84 (Figs. 6, 7 and 8) which is shown partly enclosed within a cover 85. Power is transmitted from the feed roll 28 to the take-up drive 84 through a gear train including a gear 86 fastened to the shaft 82 by a key 87, an idler gear 88 freely mounted on a shaft 89, and a gear 90 fixed to a shaft 91 by a key 92. The shaft 91 carries an eccentric pin 93 which engages a slot 94 in one end of an arm 95, the other end of which arm is pivotally mounted on shaft 82. Rotation of the pin 93 causes the arm 95 to rock back and forth through a narrow arc thereby driving a barrel cam 96 counterclockwise by means of a pawl arrangement indicated generally by reference numeral 97 and a cooperating lock pawl arrangement indicated generally by reference numeral 98. The pawl arrangement 97 includes a shaft 99 extending through and carried by the arm 95 and a pawl 101 mounted on one end of said shaft 99. Encircling the shaft 99 is a helical spring 102 one end of which is fastened to the arm 95, and the other end of which is engaged in a slot 103 formed in enlarged head 104 of the shaft 99. The spring 102 urges the shaft 99 counterclockwise and thereby moves the pawl 101 into driving engagement with teeth 106 provided on the barrel cam 96. The lock pawl arrangement 98 is similar in construction and function to lock pawl arrangement 54 and is carried by a shaft 107 having an enlarged integral head 108. A pawl 109 is mounted for rotation on said shaft 107 and a helical spring 111 encircles the said shaft. One end of the spring 111 is fastened in a slot 112 in the head 108 and the other end thereof is fastened to the pawl 109, thus urging the pawl into engagement with the teeth 106 on the barrel cam 96. The teeth 106 do not extend completely around the periphery of the barrel cam, being interrupted at two diametrically opposed points 113 and 114, as a result of which the barrel cam 96 will be driven through an angle of somewhat less than one hundred and eighty degrees by the continued operation of the pawl 97. Holes 115 are provided in the barrel cam 96 and by inserting a spanner wrench in these holes, it is possible to manually rotate the cam to any desired position.

The barrel cam 96 is slidably mounted on the shaft 82 and is provided with a camming surface 116 around its circumference. Cooperating with camming surface 116 is a camming surface 117 of a ring cam 118, the latter being mounted in the cover 85 by means of screws 119. The profiles of the camming surfaces 116 and 117 are shown in detail in Figure 11 and include two identical gradual slopes 121 separated by two sharp slopes 122 spaced one hundred and eighty degrees apart.

In the starting position with the cloth-roll 29 empty, the camming surfaces 116 and 117 will be mutually engaged as shown in the drawings. As the barrel cam 96 is rotated by the pawl 97 the camming surfaces will move relative to each other forcing the barrel cam inwardly on the shaft 82, thereby compressing a helical spring 123 which encircles said shaft, against a clutch plate 124 surfaced with frictional material 126. The clutch plate 124, which is mounted on the shaft 82 by means of a key 127, bears against and drives a gear 128 mounted on a ball bearing 129 for free

rotation around said shaft. As the spring pressure on the clutch plate 124 is increased, it will transmit a greater driving force from the shaft 82 to the gear 128. This driving force will be transmitted in turn from the gear 128 to a meshing gear 131 fixed to a sleeve 132 by a key 133. The sleeve 132 is mounted in a bearing 134 carried by the frame 34 and is provided with a keyway 136 extending along its full length. A key 137 seated in this keyway transmits the driving force on the sleeve 132 to a shaft 138 mounted therein and in turn to a universal joint 139 fastened to one end of said shaft. From the universal joint 139, the force is transmitted to an arm 141 which has one end fastened to the universal joint 139 and which has its other end fastened, by means of a second universal joint 142, to a plug 143. Said plug 143 is provided with a key 144 and stud 145 which engage a fitting 146 in the cloth-roll 29 and through which a torque is applied to said cloth-roll as knitting proceeds.

The plug 143 is free to rotate in a bearing 147 carried at one end of an arm 148. The other end of said arm 148 is provided with a collar 149 which is fastened to a shaft 150 by means of a taper pin 151. Said shaft 150 is pivotally mounted at one end in a bearing 152 and at the other end in a bracket 153 to permit the arm 148 carrying the plug 143 to rise as fabric is wound on the cloth-roll 29. Collars 154 fastened to the shaft 150 by set screws 156 are provided on each side of the bracket 153 to prevent longitudinal motion of the shaft in its bearings.

The cloth-roll 29 is supported adjacent its left end by a plug 157 provided with a key 158 and a stud 159 which engage a fitting 160 on the cloth-roll 29. Like the plug 143, the plug 157 is mounted for free rotation in a bearing 161 at one end of an arm 162 (Fig. 1), the other end of which is mounted on the shaft 150 by means of a sleeve 163. Said sleeve 163 is fastened to the shaft 150 by means of a wing-nut 164. A handle 166 is provided on the plug 157 whereby the entire assembly may be shifted along the shaft 150 to permit the cloth-roll 29 to be replaced and also to accommodate cloth-rolls of different sizes.

When knitting is to be started, an empty cloth-roll 29 is mounted between the plugs 143 and 157 and rests on the surface of the feed roll 28. At the same time, the barrel cam 96 is rotated counterclockwise by means of a spanner wrench engaging the holes 115 until the pawl 101 engages the first ratchet tooth 106 clockwise from the section 113 of the barrel cam 96. In this position of the barrel cam 96, the slopes 121 and 122 of the camming surfaces 116 and 117 will be engaged as shown in Figure 11 of the drawings and the cam will exert its minimum force on the spring 123. This in turn will result in a minimum of force between the frictional material 126 and the gear 128 and a minimum of added driving torque upon the cloth-roll 29. Depending upon the particular results desired, it is possible to have no added torque whatsoever applied to the cloth-roll 29 when it is empty, and rely solely upon the frictional drive from the feed roll 28. It is, however, generally preferable to apply some added torque to the cloth-roll 29 from the very beginning. Furthermore, it may be found desirable with some fabrics to rotate the barrel cam 96 beyond its initial point and thereby obtain a larger added torque upon the cloth-roll at the outset.

When knitting begins, the feed roll 28 will be driven in synchronism with the knitting cycle through the feed roll driving mechanism 34.

The rotation of the feed roll will operate the take-up drive 84 and supply a minimum of torque to the cloth-roll 29, the magnitude of which will depend upon the design of the take-up drive 84 and the initial setting of the barrel cam 96. As knitting proceeds, the barrel cam will be driven relative to the ring cam 118 by means of pawl 101 thereby compressing the spring 123 and increasing the force between the frictional material 126 and the gear 128. This in turn will increase the torque upon the cloth-roll 29 in proportion to the amount of fabric on the cloth-roll. The torque on the cloth-roll 29 will continue to increase until the pawl 101 reaches the section 114 of the barrel cam 96. In this position of the barrel cam 96, the spring 123 will be compressed to its greatest extent since the slopes 121 of the camming surfaces will be shifted approximately one hundred and eighty degrees relative to each other. This will result in a maximum of torque on the cloth-roll 29 which torque will remain constant at this maximum value since the continued motion of the pawl 101 will no longer be effective to drive the barrel cam 96. Satisfactory results are obtainable when a little more than half the fabric has been wound on the cloth-roll 29 before the maximum torque is reached, it having been found that no additional increase in torque is required beyond this point. After the cloth-roll 29 has been filled it is replaced by an empty cloth-roll and the barrel cam is again rotated counterclockwise until the pawl 101 has cleared the section 114 of the barrel cam 96 after which the entire cycle is repeated.

With the slopes 121 of the camming surfaces 116 and 117 linear as shown in the drawings, the added torque will also increase in an approximately linear manner. It is possible, however, to vary the increase in torque so that it is non-linear, or even to have the torque decrease if this is found desirable by altering the slopes 121 to correspond to the desired change in torque.

The angular rotation of the feed roll 28 may be adjusted for fabrics having a different number of courses per inch by replacing the ratchet wheel 52 with another wheel having a different number of teeth and simultaneously adjusting the stroke of the pawl 53 by shifting the eccentric plate 41. Any change in the angular rotation of the feed roll 28 will be accompanied by a corresponding change in the torque applied to the cloth-roll 29 since the cloth-roll is driven through the feed roll.

It is to be understood that the foregoing detailed description is given merely by way of illustration and that many variations may be made therein without departing from the spirit of our invention.

Having described our invention, what we desire to secure by Letters Patent is:

1. Fabric take-up means for warp-knitting machines and the like, the combination with a fabric take-up roll, of means for rotating said take-up roll and separate means for positively applying and additional torque to said take-up roll.

2. Fabric take-up means for warp-knitting machines and the like, the combination with a fabric take-up roll, of means operating in timed relation to the knitting cycle for rotating said take-up roll, and means operatively connected to said take-up roll rotating means for positively applying an additional torque to said take-up roll.

3. Fabric take-up means for warp-knitting machines and the like, the combination with a

fabric take-up roll, of means operating in timed relation to the knitting cycle for rotating said take-up roll, and means operatively connected to said take-up roll rotating means for positively applying an additional torque to said take-up roll at predetermined intervals.

4. Fabric take-up means for warp-knitting machines and the like, the combination with a fabric take-up roll, of means operating in timed relation to the knitting cycle for rotating said take-up roll, and means operatively connected to said take-up roll, rotating means for positively applying an additional torque of varying magnitude to said take-up roll.

5. Fabric take-up means for warp-knitting machines and the like, the combination with means for drawing the knitted fabric from the knitting station of the warp-knitting machine and a fabric take-up roll rotated by said drawing means, of separate means for positively applying an additional torque of varying magnitude to said take-up roll at predetermined intervals.

6. Fabric take-up means for warp-knitting machines and the like, the combination with a fabric feed roll and a fabric take-up roll rotated by said feed roll, of separate means for positively applying an additional torque of varying magnitude to said take-up roll.

7. Fabric take-up means for warp-knitting machines and the like, the combination with a fabric feed roll and a fabric take-up roll rotated by said feed roll, of separate means for positively applying an additional torque of varying magnitude to said take-up roll at predetermined intervals.

8. Fabric take-up means for warp-knitting machines and the like, the combination with a fabric feed roll and a fabric take-up roll rotated by said feed roll, of separate means for positively applying a torque of increasing magnitude to said take-up roll and for holding the magnitude on said torque constant after the winding on said take-up roll of a predetermined quantity of fabric.

9. Fabric take-up means for warp-knitting machines and the like, the combination with a fabric feed roll and a fabric take-up roll rotated by said feed roll, of separate means for positively applying an additional torque to said take-up roll at predetermined intervals and means for increasing the magnitude of said torque and for holding the magnitude of said torque constant after the winding on said take-up roll of a predetermined quantity of fabric.

10. Fabric take-up means for warp-knitting machines and the like, the combination with a fabric feed roll and a fabric take-up roll frictionally rotated by said feed roll, of separate means operatively connected to said feed roll for positively applying an additional torque of varying magnitude to said take-up roll.

11. Fabric take-up means for warp-knitting machines and the like, the combination with a fabric feed roll and a fabric take-up roll resting on said feed roll, of clutch means driven through said feed roll for applying a torque of varying magnitude to said take-up roll.

12. Fabric take-up means for warp-knitting machines and the like, the combination with a fabric feed roll and a fabric take-up roll resting on said feed roll, of means driven through said feed roll for applying a torque of increasing magnitude to said take-up roll and for holding the magnitude of said torque constant after a pre-

5 determined quantity of fabric has been wound on said take-up roll.

13. Fabric take-up means for warp-knitting machines and the like, the combination with a fabric feed roll and a fabric take-up roll resting on said feed roll, of clutch means driven through said feed roll for applying a torque to said take-up roll, and cam means for varying the magnitude of the torque transmitted by said clutch means to said take-up roll.

14. Fabric take-up means for warp-knitting machines and the like, the combination with a fabric feed roll and a fabric take-up roll resting on said feed roll, of clutch means driven through said feed roll for applying a torque to said take-up roll, cam means for varying the magnitude of the torque transmitted by said clutch means, and ratchet means for driving said cam means to vary the magnitude of the torque applied to said take-up roll.

15. Fabric take-up means for warp-knitting machines and the like, the combination with a fabric feed roll and a fabric take-up roll resting on said feed roll, of clutch means driven through said feed roll for applying a torque to said take-up roll, cam means for varying the magnitude of the torque transmitted by said clutch means, and ratchet means for driving said cam means to vary the magnitude of the torque applied to said take-up roll, said ratchet means having an interrupted section therein limiting the extent to which said cam means are driven, whereby the magnitude of the torque applied to said take-up roll remains constant after a predetermined quantity of fabric has been wound on said take-up roll.

16. Fabric take-up means for warp-knitting machines and the like, the combination with a fabric feed roll and a fabric take-up roll, of means driven through said feed roll for applying a torque of varying magnitude to said take-up roll.

17. Fabric take-up means for warp-knitting machines and the like, the combination with a fabric feed roll and a fabric take-up roll, of clutch means driven through said feed roll for applying a torque of varying magnitude to said take-up roll.

18. Fabric take-up means for warp-knitting machines and the like, the combination with a fabric feed roll and a fabric take-up roll, of means driven through said feed roll for applying a torque of increasing magnitude to said take-up roll and for holding the magnitude of said torque constant after a predetermined quantity of fabric has been wound on said take-up roll.

19. Fabric take-up means for warp-knitting machines and the like, the combination with a fabric feed roll and a fabric take-up roll pivotally mounted to rest on said feed roll, of a friction clutch driven through said feed roll for selectively applying a torque to said take-up roll, a barrel cam and a mating ring cam for increasing the clutch pressure endwise of said friction clutch to thereby increase the magnitude of the torque applied to said take-up roll, ratchet teeth having an interrupted section carried by said barrel cam, a ratchet pawl driven through said feed roll for driving said barrel cam through engagement with said ratchet teeth to increase said clutch pressure, the interruption in said ratchet teeth limiting the extent to which said ratchet pawl drives said cam to thereby hold the magnitude of said torque constant after a pre-

2,652,704

9

determined quantity of fabric has been wound
on said take-up roll.
